CONTROL MEANS FOR AIRPLANES

Giuseppe M. Bellanca and John Bellanca,
New Castle, Del.Application September 21, 1937, Serial No. 164,950
Renewed April 16, 1940

6 Claims. (Cl. 244—90)

This invention relates to airplanes, more particularly to an improved type of control means for airplanes.

As is known, the essential control of an airplane about the lateral axis is achieved by means of ailerons. These are of two general types, the long, narrow type, which extends across the trailing edge of the wing for a considerable span, and the short type mounted near the wing-tip. Each type has certain advantages which may recommend its use to any particular design of plane.

In recent years, considerable interest has developed in wing flaps. As is known, the trailing edge flap is a member which is connected to the rear portion of the wing and is adapted to be depressed or lowered so as, in effect, to markedly modify the camber of the main wing, thus increasing the lift of such wing and, by concomitantly increasing the drag, very markedly lower the critical take-off and landing speeds.

Despite the real potentialities of the flap, its full value had not been, and, in the nature of prior designs, could not be attained. The effect achieved from mounting a flap on the wing, in the very nature of its operation, depends on its size. The greatest effectiveness is achieved by having the flap extend substantially the full span of the wing. In the typical designs of planes, however, this is impossible, since not an inconsiderable portion of the available trailing edge of the wing must be allocated to the aileron in order to insure proper lateral control. The utilization of a flap and an aileron on the same wing has therefore represented a none too satisfactory compromise between maximum potential flap and aileron efficiency respectively. As those skilled in the art know, assembling a flap and aileron, on the wing in necessarily closely juxtaposed position, causes undesired air flow reactions of each member on the other. Therefore, in the past full potential benefits of flap operation have not been secured.

We have found that the maximum advantages of the function of a flap may be secured and that, furthermore, additional advantages, particularly in the attainment of low landing and take-off speeds, may be secured by utilizing a flap and correlating this in a special manner with a novel type of lateral control means or aileron construction. As will be seen more fully, the concept of the present invention involves the utilization of any desired section of the trailing edge of the wing, and up to the full span, for flap action, and utilizing a heretofore unemployed area, namely, the wing tip and its lateral

projection as the zone of action of the aileron. In this manner, as will be appreciated, the ailerons are displaced from the flaps and do not engender the undesirable airflow reactions that have obtained in the past. Furthermore, as those skilled in the art will appreciate, utilization of ailerons in the wing tip area presents at once the combined advantages of the long and short flap.

In order to enable a more ready comprehension of the invention, a typical physical embodiment is shown in the accompanying drawings, of which:

Figure 1 is a plan view of an airplane embodying the invention.

Figure 2 is a similar plan view, showing the ailerons in operative position.

Figure 3 is a similar view, illustrating the joint use of ailerons and flaps for securing low landing and take-off speeds.

Figure 4 is a lateral cross-section of the main airfoil or sustentation surface.

Figure 5 is a cross-section taken on line 5—5 of Figure 4.

Figure 6 is a horizontal section taken on line 6—6 of Figure 4.

Figure 7 is an enlarged detail of a portion of the aileron operating means.

Figure 8 is a schematic view of an illustrative aileron operating linkage.

Figure 9 is a diagrammatic illustration of the mechanism for effecting simultaneous operation of the ailerons.

As indicated, the improvements contemplated herein may be embodied in a typical land or sea plane, for purposes of illustration the improvements are shown as incorporated in a land plane. Such plane may comprise a fuselage which is provided with airfoils 2, empennage 3, landing mechanism 4, and a suitable power plant 5 for driving the propeller 6. For simplicity, the invention will be described as embodied in a monoplane but it will, of course, be appreciated that the improvements contemplated herein may be utilized in any type of multiplane.

As shown in the drawings, the flaps 6 are pivotally mounted adjacent the trailing edge of the wings 2, in any suitable manner such that, in retracted position, they are substantially comprised within the contour of the main airfoil, and are adapted to be rotated downwardly, by suitable mechanism, to the operative position. It is particularly to be observed that such flaps 6 may extend the full fixed span of the wing, thus permitting maximum flap effect. In

the present mode of construction, as will be seen, the ailerons impose absolutely no limitations on the length of the cord of the flaps, such maximum length being determined only by the span of the main wing itself.

In achieving lateral control, a new aileron principle is invoked. Briefly considered, this comprises the utilization of the laterally slideable or movable ailerons 7 and 8. The ailerons are adapted to be moved either independently or simultaneously from a position nested within the main airfoil, laterally outwardly to any desired extended position.

With this type of operation, it will be appreciated that most effective lateral control is achieved. Such control is accomplished, in a sense, by providing main airfoils of optionally variable span. Those skilled in the art will be quick to appreciate the mode of operation of such units. For example, referring to Figure 2, assuming that it is desired to bank to the left, suitable pilot control mechanism may be operated to cause the ailerons 7 to move from the position shown in Figure 1 to that shown in Figure 2. In these circumstances, the right wing then has a greater effective lifting surface and an increased lifting movement is imposed on the right side of the plane. Since the aileron is effective at the outermost part of the wing, the maximum mechanical advantage of a long lever arm is secured.

It has been found that the lifting effect of an aileron on one wing may be advantageously correlated with means on the other wing to impose on such latter wing an increased drag, thereby imparting a desirable yawing moment to the plane. For this purpose, as will be seen more particularly from an inspection of Figures 1 and 2, the leading spar 9 (and, if desired, the trailing spar 10) are extended so that sections 9' and 10' project slightly beyond the tips of the fixed main airfoils. This projection or projections may comprise integral parts of the separate spars or may be separate members, attached to the spars and/or ribs. Preferably, they consist of flat or non-streamlined prolongations or one or more of the spars; it will be understood, however, that, to secure the functions to be described, this is not essential, since any non-streamlined projection member may be employed. It will also be understood that the design of the projections 9' and 10' may be so conformed as to secure any desired degree of drag.

As will be seen, from an inspection of Figure 1, the ailerons are so mounted that, for normal horizontal flight, each aileron projects a slight, equal distance beyond the wing tip, such distance being at least that which is necessary to cause the streamlined ailerons to enclose the non-streamlined, drag-inducing projections 9' and 10'. In these circumstances, that is to say, when the ailerons are in the position shown in Figure 1, the plane is in lateral dynamic balance.

When the ailerons are in the position shown in Figure 2, that is when aileron 7 is projected outwardly of the wing tip and the aileron 8 is simultaneously retracted with the airfoil, there is immediately and simultaneously imposed an increased lifting effect on the right wing and a markedly increased drag on the left. It is particularly to be observed that this type of reaction is quite different from that obtaining in the ordinary aileron. In these latter circumstances, operation of the typical aileron on, say, the right wing, effects an increased lift, but such increased lift is accomplished by a corresponding increased

drag. Since the aileron on the left side is not operated and is therefore within the streamlines contour, the left wing, i. e., the low drag wing, tends to move more rapidly than the right (high drag) wing. In the present, improved, construction, however, by invoking the concept of the utilization of members (9' and/or 10') which positively insure a marked and predetermined drag, a novel and beneficial correlation of drag and lifting, on respectively opposite sides of the plane, is achieved.

It will be observed that the flaps 6 are available for unrestricted operation during any of these periods when the ailerons 7 and 8 are in the different positions described.

As has been indicated hereinbefore, this type of aileron control presents an opportunity for a special and particularly advantageous correlation with the flaps for the purpose of securing a marked diminution of the critical flying speed. As shown in Figure 3, this type of construction enables the simultaneous operation of the flaps to the high lift position with the full and simultaneous projection of the ailerons. Thus, assuming that it is desired to land at a minimum speed, the ailerons 7 and 8 may be simultaneously operated (in a manner more particularly to be described) so as to be projected outwardly to their full extent. In these circumstances, the plane is in lateral balance, but by using a markedly increased wing area the lifting effect of each wing is equally increased, and to a marked degree. Depression of the flaps at this particular period of the flight further increase the lifting of the wing, as well as the drag, allowing minimal flying speeds.

The different described positions of the ailerons may be secured in any suitable manner. One effective, though illustrative, method is shown in Figure 8. As is there shown, the ailerons 7 and 8 are constructed of a size which is suitable for the particular plane in which they are used. The structural features of the aileron may, of course, vary in a manner known to skilled designers. Such ailerons may comprise, in effect, diminutive airfoils. These ailerons are ruggedly constructed and are provided with a suitable truss framework extension, designated generally by the numeral 11. Such extension may comprise the beams or braces 12 and 13, constructed of suitable materials such as high strength nonferrous alloys, and the like. To these may be connected a member 14. This framework may be rigidified and strengthened by the strut members 15 and 16. The members 12 and 13, as will be seen from an inspection of the drawings are utilized not only as rigidifying structural elements for the aileron, but also as a means for guiding the ailerons in their lateral movement. For this purpose, the ailerons are provided with the spar members 17 and 18, the latter being additionally strengthened and rigidified by the struts 19 and 20 respectively.

The main framework 12—13—14 is adapted to be connected, as through the pivot 21, to the laterally operating member 22. Member 22 is connected with a mechanical linkage, more particularly to be described, whereby it may be moved in a lateral plane at the option of the pilot. It will be observed from an inspection of Figures 6 and 8 that the member 17 is spaced from the adjacent member 12 and that similarly the member 13 is spaced from the adjacent member 12 of the aileron operating frame. The aileron itself is provided with the slots 23 and 24 which, 75

in effect, form a continuation of the gap or space between members 12 and 17, on the one hand, and members 18 and 19 on the other.

As noted hereinbefore, any suitable mechanism may be employed, by which the ailerons may be independently or simultaneously moved outwardly of the wing tip. A typical illustrative example of such independent or simultaneous operation of the two ailerons is shown in Figure 8. The operating rods 22, as shown, are each pivoted to a long arm of the bell crank levers 30. Such bell crank levers are pivoted at 31 to yokes 32. These yokes are formed with the end guiding flanges 33 and 34, which are adapted to nest or fit within corresponding grooves in the fixed frames 35 for vertical movement therein. The yokes 32 are internally threaded to receive the screw threaded members 36. These, as shown, project through the casings 35 and are provided with the bearings 37. The upper end of the shafts 36 are provided respectively with the beveled gears 38. One of the beveled gears 38 meshes with a beveled gear 39, keyed or otherwise fixed to the operating shaft member 40, which in turn is operated through suitable mechanism by the hand wheel or other manually operable member 41. A shaft 42, provided at each end with the bevel gears 43 and 44, extends between the two screw shafts 36. With this type of linkage, it will be observed that the operation of the hand wheel 41 or other member will cause rotation of each of the threaded shafts 36 to effect simultaneous upward or downward movement of the two yokes 32, and correspondingly move the bell crank pivots 31 upwardly and downwardly (see Fig. 9).

As noted above, the bell crank levers are connected to yokes 32 which may constitute fixed or movable fulcra. The short arm 50 of each bell crank lever is provided with a pin 51, which fits in a slot in arm 52. The arm 52 is thus connected to each bell crank through a pin and slot or other equivalent overrunning connection. The arm 52 is keyed or otherwise rigidly connected to the rod 53, mounted for rotation in suitable bearings 54. The other end of this rod is connected to the typical stick 55. The stick 55 is provided with a yoked rod 56 which is connected in the usual manner to the elevators in the empennage.

The operation of this structure will have been appreciated from the foregoing description. When it is desired to bank the plane, the pilot moves the stick 55 laterally to the left or right, depending on the bank desired. Assuming that the stick 55 is moved to the left (Fig. 8), the connecting rod 53 is then correspondingly rotated in a counter-clockwise direction. In these circumstances, the bell crank lever 30 at the left of Figure 8 is rotated in a clockwise direction and the bell crank at the right is rotated in a clockwise direction, as illustrated by the dash-lines A and B of Figure 9. Due to the linkage, the aileron 8 is then extended and the aileron 7 is retracted. Movement of the stick 55 in the opposite direction causes, of course, a reversal of these movements.

When it is desired to extend the two ailerons simultaneously so as to secure the low landing speed desired, the member 41 is operated. In these circumstances, when the wheel 41 is operated, the yokes are simultaneously elevated and caused to ride in their guideways 35. Since the inner ends of the short arms of the bell cranks are retained against vertical movement, such operation of the wheel 41 (as particularly illus-

trated in Figure 9) causes the long arms of the two bell crank levers to move outwardly as indicated by the dotted line position C and D. In other words, the long arm of bell lever C moves clockwise, and the long arm of bell crank lever D moves counter-clockwise. The movement of each of these levers being, of course, equal. During such movement, the pins 51 of the levers slide in their corresponding slots. In this manner, the wheel or crank 41 may be operated to move each aileron an equal distance outwardly of the wing tips. It will be noted that the member 41 may also be utilized to determine the normal horizontal flying position of each of the ailerons, 7 and 8.

The mechanism shown in Figure 8 and described herein, as will be appreciated, is merely illustrative of any similarly functioning structure.

In order to secure the operations hereinbefore described, the main airfoil is so constructed to provide a guiding means for the slideable ailerons. An example of a typical and suitable construction is shown in Figures 4, 5 and 6. As shown in Figure 5, the main airfoil may be of any suitable type of construction, for example, provided with the leading edge spar 60 and the trailing edge spar 61. The spars may be attached to the wooden or metal ribs 62, in any approved manner. The structure may be rigidified by the rigidifying strut 63.

The internal structure of the aileron may be of any desired type and may comprise, as is shown in Figure 6, one or more tubular spar members 70, and the associated ribs 71. The ribs may be attached to the plates 72, 73 and the like, so as to provide a gap or space 74, forming a guideway, whereby the aileron is guided in this lateral movement.

As shown, particularly in Figures 5 and 6, the main spars 60 and 61 are provided with an extension 80 (only one being shown) which projects an appreciable distance beyond the wing tip 81. This member 80 is preferably flat or nonstreamlined and may be of a depth, and as here shown, may be substantially equal to the camber of the aileron. While the aileron is shown with the gaps or open guideways 74, it will be understood that the guiding member or spar extension 80 may be somewhat shortened and a continuous canvas skin provided on the aileron.

The aileron is provided with a series of rollers 90 and 91 which are attached respectively by means of the pivots 92 to the frame members 12 and 17. Preferably, such rollers are of a low friction type and may comprise the ball-bearing type of structure, as shown in Figure 7. As shown in Figure 5, a portion of the main spar is cut away to provide the slot 93. Such slot, in effect, providing an upper edge guideway 94 and a lower edge guideway 95. The rollers 90 and 91 are provided with the flange-bearing surfaces which are adapted to contact the guide edges 94 and 95 in the manner shown. The slot 93 is, as shown, elongated a sufficient distance to permit maximum outward and inward movement of the aileron. When the operating mechanism is actuated in the manner heretofore described, the aileron may be moved outwardly and inwardly. For example, referring to Figure 5, as the rod 22 is pulled inwardly of the plane, the rollers 90 and 91 ride upon the guideways 94 and 95. Since the rollers are attached directly to the aileron, this latter is retracted inwardly of the plane. During this movement, the wing spar projection 80 (or equivalent member) serves as a supplemental guiding means for 75

the aileron. When the aileron is in the extended position, the wing spar extension 80 (or equivalent) serves as, in effect, a fixed spar for the aileron, imparting to this latter member the necessary structural rigidity.

On the other hand, when the aileron is in fully retracted position the flat or non-streamlined member 80 projects outwardly of the tip of the aileron and, in the manner explained, serves to materially increase the drag of the wing. In the normal horizontal flying position, as will be appreciated, the ailerons are each retracted to the position where the edge of member 80 coincides with, or is within, the tip of the aileron.

15 While it is not shown, it will be understood that additional vertical rollers, or other anti-friction means, may be interposed between the flanges 12 and 17 and the vertical webs 97 and 98 of the spar construction.

20 The mechanism described is of course given as merely one illustrative and operable embodiment of the invention. Other specifically different methods of mounting the ailerons and effecting their lateral movement may be utilized.

25 It will be understood that the flaps 6 are provided with any suitable pilot controlled mechanism (not shown) whereby they may be operated at any stage in the flight of the plane.

It will be appreciated that an airplane, constructed according to the principles of the present invention, presents many advantages and a high operative efficiency. The novel aileron construction is most effective, since each aileron, in effect, is operative on the end of a long lever,

35 thus insuring immediate lateral control with minimum aileron area. The allocation of the ailerons is so correlated with the position of the flaps that full aerodynamic efficiency of each is assured, in that, with this location of the two units,

40 there are no negative aerodynamic reactions of one upon another. Similarly, as noted, the aileron construction is such that it insures a lift-inducing force on one side of the longitudinal axis and a simultaneous drag-inducing force on

45 the other, thus positively establishing an advantageous yaw. Likewise, the aileron construction is such that, at the option of the pilot, it may be employed to simultaneously increase the lift on each side of the plane. This function,

50 coupled and correlated with the flap operation, insures a marked diminution of the critical flying speed, thus establishing a low landing and take-off speed. All these advantages are secured with a structure which is as simple and practical

55 as it is effective.

Therefore, while preferred modification of the invention has been described, it is to be understood that this is given merely to exemplify the principles involved, and not as defining the exclusive means by which the principles may be effectuated.

We claim:

1. An airplane wing comprising an airfoil and an aileron normally nested largely within the contour of the airfoil and movable along the span thereof to an operative position beyond the airfoil tip and a guide member for the aileron, 5 of non-streamlined form, projecting laterally beyond the wing tip.

2. An airplane comprising a fuselage, main airfoil attached to the fuselage at each side thereof, lift-inducing and drag-inducing means on 10 each wing, said drag-inducing means being nested within the said lift-inducing means, and means simultaneously to effect the operation of the lift-inducing means on one wing and the drag-inducing means on the opposite wing. 15

3. An airplane comprising a fuselage, main wings attached to the fuselage at each side thereof, an aileron mounted within each wing near the wing tip, guide means for the aileron extending beyond the tip of the wing; means to simultaneously extend the aileron of the one wing to a position outwardly of the wing tip to impose a lifting movement on such wing, and to retract the other aileron within the body of its associated wing to expose the said guide means to thereby 20 impose a predetermined drag on such wing. 25

4. In an airplane having a fuselage and a wing on each side thereof, an aileron mounted within each wing and movable along the span thereof, and drag-inducing members projecting beyond 30 the wing tip and means to expose such members by lateral movement of the aileron to optionally increase the drag of a wing.

5. In an airplane having a fuselage and a wing on each side thereof, ailerons mounted 35 within each wing, such ailerons being adapted to slide along the span of the wing and outwardly of the wing tip; drag-inducing members attached to the wing and projecting beyond the wing tip; means to simultaneously extend one 40 aileron to increase the lift of its associated wing, and to retract the other aileron to a position to expose the said drag-inducing means to the air stream to thereby increase the drag on its associated wing. 45

6. An airplane comprising a fuselage, main wings attached to the fuselage on each side thereof, pivoted trailing edge flaps attached to the wings and extending substantially the full span, ailerons nested within each wing, such ailerons 50 being adapted to slide along the span of the wing and outwardly along the wing tip; drag-inducing members attached to the wing and projecting beyond the wing tip; means to simultaneously extend one aileron to increase the lift of its associated wing, and to retract the other aileron to a position to expose the said drag-inducing means to the air stream to thereby increase the drag on its associated wing. 55

60 GIUSEPPE M. BELLANCA.
JOHN BELLANCA.
